UNITED STATES PATENT OFFICE.

BENEDICT FULIGNI AND CARL J. MUHSGNUG, OF NEW YORK, N. Y.

AUTOMOBILE-REFLECTOR DIMMER.

1,336,951.

Specification of Letters Patent. Patented Apr. 13, 1920.

Application filed September 18, 1919. Serial No. 324,482.

To all whom it may concern:

Be it known that we, BENEDICT FULIGNI, a citizen of Italy, residing in New York, county of New York, and State of New York, and CARL J. MUHSGNUG, a citizen of the United States, residing in New York, county and State of New York, have invented new and useful Improvements in Automobile-Reflector Dimmers, of which the following is a specification.

This invention has as its object to provide means for projecting and directing the rays from powerful lamps, as automobile headlights, angularly downward and straight in advance when they are required, preventing the blinding glare from a plain lens covered reflector so often encountered.

A further object is to attain a dimming or screening effect from a point substantially level with the light, this effect being intensified in a constantly increasing ratio as the view point is raised with respect to the lamp, the light from which is not diminished but merely directed in its proper path.

These and other like objects are attained by the novel construction and combination of parts hereinafter described and shown in the accompanying drawings, forming a material part of this disclosure, and in which:

Figure 1 is a partial side elevational and partial vertical sectional view taken through a lamp reflector and dimmer made in accordance with the invention.

Fig. 2 is a front elevational view of the same.

Fig. 3 is a fragmentary perspective view showing the construction of the screen elements, and

Figs. 4, 5 and 6 are fragmentary perspective views drawn to enlarged scales showing modified forms of the screen apertures.

Referring to the drawings in detail, the numeral 10 indicates the outer casing or shell of a conventional type of automobile headlight, the same being supported on a stand 11, combined with an attaching bracket 12, adapted to be secured to the forks or other suitable portion of the vehicle.

A beading 14 is formed with the casing 10, from which extends an annular ring or band 15, the same forming a support for the clamp ring 16, having an arcuate, concavo-convex outer surface 17 and containing in its inner concave side an annular flanged bracket 18, secured by screws or like fasten-

ings, and having a foot element 19 engageable with the correspondingly shaped flange 20 of the reflector 21, which is of the usual concave type having a highly finished inner surface.

A light, indicated by the electric lamp 23, is secured in the socket 24, contained between the outer shell or casing 10 and the rear wall of the reflector 21, is fed by an electric current received through the wire 25. All of the several foregoing parts are of the usual standard type of construction and do not constitute part of the present invention.

A circular transparent plate 26 of glass is held in position within the interior of the reflector by the inturned terminal edge of the clamp ring 17, the same preventing the entrance of dust, rain and the like to the interior of the reflector, and permitting the light rays from the lamp 23 to pass freely outward.

A screen plate 28 having beveled edges suited to the contour of the interior of the reflector 21, is provided with thin annular extending flanges 29, the same being of uniform thickness and adapted to be disposed between the flange 20 and the glass plate 26, suitable padding or packing being interposed at the joints so as to prevent fracture, either of the screen or the transparent plate.

This screen plate, which constitutes the dimmer element, is of considerable thickness and contains a plurality of juxtaposed openings or cells 30 between the vertical walls which are arranged in parallel relation, as shown in Figs. 1, 2 and 3, in connection with transversely disposed walls 32, these last named walls being slanted downward and outward at an angle of from 10 to 15 degrees to the axis of the reflector.

This screen has the appearance of a honeycomb, and the thickness of the plate 28 is approximately three times the diameter or distance across from wall to wall, of the openings.

If it be preferred, the plate 28 may be formed with circular cells 34, as shown in Fig. 4, diamond shaped, as at 35, in Fig. 5, or elliptical, as indicated by the numeral 36 in Fig. 6, or in fact of any symmetrical geometrical cross section which may be preferred, and in which the vertical walls are arranged parallel with the central axis of the reflector while the horizontal walls are

directed downwardly in the manner indicated, for the purpose of projecting the light rays in advance of the lamp slightly downward and directly outward.

5. Obviously the angle of the openings must not be too accentuated as it is desirable to dispense the light rays at a considerable distance in advance of the vehicle, fifty feet or thereabout, for practical purposes, and 10 dimmed or partially obscured at a point above the axis of the lamp so that people in another vehicle or pedestrians are not blinded or discommoded by the glare of the direct rays in a manner which will be 15 clearly understood.

This disclosure is to be regarded as descriptive only and not as restrictive or limitative of the invention, of which obviously an embodiment may be constructed including many minor modifications without departing from the general scope herein indicated and hereinafter claimed.

20 Having thus described our invention and set forth the manner of its construction and 25 application, what we claim as new and desire to secure by Letters Patent, is:—

1. In a dimmer for headlights, the combination with a reflector, a lamp mounted

therein, and a transparent cover at the outer portion of said reflector, of a grid plate 30 secured in said reflector adjacent to said transparent plate, said grid plate containing openings having symmetrical geometrical cross sections formed with vertical walls parallel with the plane of said reflector and 35 horizontal walls directed downwardly at an angle thereto, the openings in said plate extending coincident with its entire area.

2. In an automobile reflector, the combination with a hollow concave casing, a lamp disposed therein, and means for producing a light in said lamp, of a transparent plate fixed upon the outer edges of said reflector casing, a relatively thick opaque plate suited to be received within the reflector body, an annular flange formed on said plate, and means for securing said flange in intimate relation with said reflector, said plate containing honeycomb-like through openings, the mentioned openings throughout its full area being directed angularly downward from the rear to the front.

In testimony whereof, we have signed our names to this specification.

BENEDICT FULIGNI
CARL J. MUHSGNUG.
